UNITED STATES PATENT OFFICE.

DAVID W. BLOMQUIST, OF SEATTLE, WASHINGTON.

DESIGN FOR A SERVICE-PIN.

• 54,585.

Specification for Design.

Patented Mar. 9, 1920.

Application filed May 20, 1919. Serial No. 298,565. Term of patent 3½ years.

To all whom it may concern:

Be it known that I, DAVID W. BLOMQUIST, a citizen of the United States, and a resident of Seattle, in the county of King and the State of Washington, have invented a new, original, and ornamental Design for Service-Pins, of which the following is a specification, reference being had to the accompanying drawing, forming a part thereof.

In the drawings, the figure is a face or plan view of the pin showing my new design.

I claim:

The ornamental design for a service-pin, as shown.

DAVID W. BLOMQUIST.
